Fig. 3.

Inventor
Henry C. Band
by Otto M. Normand, Atty.

UNITED STATES PATENT OFFICE

HENRY C. BAND, OF CHICAGO, ILLINOIS, ASSIGNOR TO C. H. HANSON COMPANY, OF CHICAGO, ILLINOIS

INDICATOR

Application filed May 31, 1928. Serial No. 281,746.

The invention relates to indicators and has as its prime object the provision of a device of this character with means whereby said device may readily be secured to some convenient portion of an automobile such as the material forming the lining of the body of the car, and which device may be set to thereby provide information as to the period at which to perform some duty such, for instance, as the period at which to change the lubricant for the engine of the car, or to provide means which may be readily operated while attached to the person to provide means to assist in keeping count of any of various other matters of count such as the number of strokes in the playing of the game of golf.

The invention has as a further object the provision of a mounting element to which the counter wheels are attached, the mounting element being formed to provide and maintain a space between it and the material to which the device is attached, in which space the counter wheels may operate without interference between said wheels and the material.

The invention also has as an object the provision of a counter device having means whereby said device may be attached to the material or some portion of wearing apparel, said means permitting the ready association and disassociation of the device and the material or wearing apparel, and preventing the accidental disassociation of the device therefrom.

In addition, it is an object to provide a device of the character above described, with means which may be passed through the lining or material or may be passed over an edge of a part of wearing apparel, such as a belt, to thereby hold the device relatively thereto.

The invention also has as an object the provision of a yieldable holding means formed in a manner to successfully hold the device in place.

The invention has these and other objects, all of which will be explained in detail and more readily understood when read in conjunction with the accompanying drawings

forming a part hereof, it being obvious that changes and modifications may be resorted to without departing from the spirit of the appended claims forming a part hereof.

In the drawings,

Fig. 1 is a front elevation of a device constructed according to one embodiment of which the invention is susceptible, a portion of the construction being broken away for the purpose of illustration;

Fig. 2 is a plan view of the device shown in Fig. 1, and

Fig. 3 is a section taken on line 3—3 of Fig. 1.

The embodiment of the invention as illustrated in the drawings contemplates the use of a plate 10, which provides a support for a plurality of discs 11—11, each of which is provided with indicia, and which is rotatably secured to the plate as indicated at 12. These discs or counter wheels are arranged in parallel rows along said plate and have a portion of their edges extended beyond the opposite edges of the plate to thus permit them to be engaged to cause their rotation. Said plate is provided with a plurality of apertures 13—13, one of which is located adjacent an edge of each counter wheel to thus provide means whereby certain indicia provided upon the faces of said counter wheels may be viewed.

The opposite ends of said plate 10 are bent laterally toward the counter wheels as indicated at 14, and are also bent outwardly as indicated at 15 parallel with the body of the plate. This construction of the ends of said plate provides a recess 16 in which the counter wheels are rotatably located, and in addition provides, through the medium of the outwardly extending lip or flange 15, a means which assists to maintain the plate and said counter wheels in separated relation to the fabric 17 which, as before stated, may be the lining of an automobile body. Means is provided for attaching and securing the device thus far explained to said lining. This means may be in the form of a pointed element or prong 18, one of which is located adjacent the opposite ends of the plate and formed to provide the laterally extended part

19 which is connected to the plate adjacent to the upper edge thereof and extended beyond the rear face of the plate and is bent to provide the downwardly extending part 20, this latter portion being spaced from the body so that the material or fabric of the lining may be located between said prong and the laterally extending lip or flange 15 and thus hold said material extending between said prongs in its proper spaced relation to the indicator wheels so that no interference between these portions will result.

The laterally extending part 19 will, when this prong is passed through the fabric, provide means for preventing the accidental removal of the device from the fabric. It is manifest that the device may be secured to a belt or other similar article having an edge by passing said downwardly projecting portion 20 of the prong over the edge of the belt to thereby hold the device in associated relation with said belt.

From the foregoing description of the invention, it is manifest that an extremely simple arrangement is provided which may be attached to the lining of an automobile body or to a belt or other garment and thus provide means which, in the event of the first mentioned use, may be set to advise the automobilist as to when a change of lubricant is advisable, and also that when the device is employed by golfers, it may be attached readily to the belt of the player or some other portion of his apparel and thus provide means whereby an accurate count of his score may be kept.

It is evident that the structure employed is such that the counter wheels are held in spaced relation to the material to which the device is attached so that interference between said counter wheels and the material is prevented.

Having described the invention, what I claim and desire to cover by Letters Patent is:

55 1. In an indicator, the combination of a plate providing a support, indicator wheels, said wheels being arranged upon one side of the plate and relatively to an edge thereof to locate a portion of the periphery of said wheels beyond an edge of said support, apertures provided in said plate through which a portion of said wheels may be viewed, said plate having opposite edges thereof bent toward and beyond said wheels to provide a recess in which said wheels are mounted for rotation, and a holding element extending from that side of the plate to which said wheels are secured.

2. In an indicator, the combination of a plate providing a support, said plate having opposed ends thereof bent to provide a recess between said ends, a plurality of indicator wheels provided in said recess, said indicator wheels being located relatively to the edges of the recessed portion of the plate to arrange a portion of the periphery of said wheels be-

yond opposite edges of said recessed portion, apertures provided in said plate adjacent each wheel, and a holding element projecting from said plate beyond said wheels.

3. In an indicator, the combination of a supporting plate, a plurality of indicator wheels secured to one side of said plate and arranged in rows lengthwise of said plate, an aperture provided in said plate adjacent each wheel, said wheels being mounted relatively to longitudinal edges of said plate to arrange a portion of the periphery of said wheels beyond said edges of said plate, the ends of said plate being bent toward and beyond said wheels to provide a recess in which said wheels are mounted, and a holding element arranged at each end of said plate, said holding element being spaced from that side of said plate upon which said wheels are mounted.

In witness whereof, I hereunto subscribe my name this 22nd day of May, A. D. 1928.

HENRY C. BAND.
